Colo.; now by change of name Mary Ravenscroft Riddle

Application January 24, 1952, Serial No. 18,192

Term of patent 14 years

(Cl. D35—1)

To all whom it may concern:

Be it known that I, Mary Evalyn Ravenscroft, a citizen of the United States, residing at 1926 Cheyenne Boulevard, Colorado Springs, Colorado, have invented a new, original, and ornamental Design for a Garden Marker, of which the following is a specification, reference being had to the accompanying drawing, forming a part hereof.

Fig. 1 is a front plan view of a garden marker, embodying the features of my new design;

Fig. 2 is a side view;

Fig. 3 is a perspective view of the garden marker.

I claim:

The ornamental design for a garden marker, substantially as shown.

MARY EVALYN RAVENSCROFT.
